UNITED STATES PATENT OFFICE.

FRANK M. SLOUGH, OF ROCHESTER, NEW YORK, ASSIGNOR TO THE STROMBERG-CARLSON TELEPHONE MANUFACTURING COMPANY, OF ROCHESTER, NEW YORK, A CORPORATION OF NEW YORK.

RINGING-TONE CIRCUITS.

1,354,347.

Specification of Letters Patent. Patented Sept. 28, 1920.

Application filed December 1, 1916. Serial No. 134,227.

To all whom it may concern:

Be it known that I, FRANK M. SLOUGH, residing at Rochester, in the county of Monroe and State of New York, a citizen of the 5 United States, have invented certain new and useful Improvements in Ringing-Tone Circuits, of which the following is a full, clear, concise, and exact description, reference being had to the accompanying drawings, forming a part of this specification.

It has been proposed in improved telephone systems to so arrange the central office apparatus that the subscriber shall hear in his telephone receiver the sound of 15 a ringing bell; this for the purpose of reassuring the calling subscriber that the call is being sent to the telephone of the called subscriber in the proper manner and that the called subscriber's bell is ringing. It 20 has been proposed to do this by arranging a ringing bell and a telephone transmitter in close proximity one to the other, the transmitter circuit being arranged to include a source of current and the necessary 25 conducting wires, coils, etc., which are usual in telephonic transmitting circuits.

It has been further proposed to arrange the above apparatus in the central office where connections are completed by the act 30 of a telephone operator, or by automatic means. Means have also been proposed for connecting to the line of the calling subscriber the tone transmitting circuit, so that the tone produced by the ringing bell may 35 be projected over the line of the calling subscriber and heard in the receiver of the calling line telephone.

However, the above arrangement has been far from satisfactory, due to the fact that 40 the transmitter transmits not only the sound of the ringing bell but also the pounding sound which is produced by the impact of the bell tapper upon the bell gong, consequently the sound received by the calling subscriber is not the clear, ringing tone of 45 the bell, but rather largely a confused pounding noise produced by the impact of the gong tapper upon the gong. It has been found that in all arrangements of the kind proposed 50 that the pounding sound predominates and that very little of the ringing tone can be heard above the sound produced by the impact.

It is particularly the object of this in-

vention to produce a tone device which will 55 permit the clear, ringing tone of the bell without the tone being obscured in any way by the sound of the impact of the tapper upon the gong.

I have shown an embodiment of my invention in the accompanying drawing, in which Figure 1 is a plan view of a bell constructed in accordance with my invention. Fig. 2 is a circuit diagram of an embodiment of my invention as applied to a 60 manual telephone system. Fig. 3 is a circuit diagram of an embodiment of my invention as applied to a manual telephone system in which the ringing is intermittently applied by an electromagnetic key.

In the drawings "G" represents a gong at the central office which is caused to sound by the impact of a tapper *t*, the same being mounted upon an armature *a*, which is caused to vibrate by virtue of the intermittent attraction of the magnet coils *m*, as controlled by the controlling contacts *c*. The energizing circuit of this bell is that of the ordinary and well-known vibrating bell, and contains a source of current *E*, and 65 needs no detailed description, being well-known in the art. The well-known closed circuit form of bell is shown in Fig. 1, and this type of closed circuit bell being indicated at *C*. A magneto bell operated by 70 alternating current could obviously be employed.

Referring to the figures, I show an extra set of contacts as composed of a spring *S* and associated spring *e*, the two contacts of 75 the springs being so adapted to make an electrical connection when the tapper is at that part of its stroke distant from the gong, and which is adapted to break this electrical contact when the tapper is striking the gong. At "T" I show a telephone transmitter which may be of any of the well-known 80 types. This transmitter is arranged in close proximity to the vibrating or sounding gong *G*. This transmitter may be merely a transmitter button whose electrode, which is capable of movement, can be mechanically connected to the gong *G*. In Fig. 2, at "C" I show a certain apparatus and circuit connections which form a transmitting circuit composed of apparatus as follows: A condenser *k* and an induction coil *i*, having a primary winding *p*, and secondary wind-

ing s , impedance coils l and a source of current E_1 . The electrical contacts between the spring S and the contact c_1 are here shown in that part of the transmitting circuit which 5 leads to the primary winding p of the induction coil i . Condensers k_2 are connected in the circuit of the secondary winding s and in the wires w and w_1 which lead to the telephone switchboard. Terminal binding 10 posts b and b_1 are shown at the point where the various taps are made from various switchboard connecting circuits to the common tone transmitting circuit C just discussed. At "O" I show an operator's switch- 15 board connecting circuit, which is here shown connecting a telephone sub-station at "A" to a telephone sub-station at "B." The connection is here shown as being made by means of plug and jack switches shown at 20 "J" and "J₁." At the station "A" the subscriber's apparatus is shown in a connected position, the switch-hook contacts h connecting the receiving apparatus to the line wires being closed, and at "B" the telephone apparatus 25 is shown in its retired position, with the switch-hook contacts h_2 open, and the sub-station bell at "B" connected across the line, and as the circuits are shown in Fig. 2, the bell b is being operated by current from 30 a ringing generator D at the central office. The sub-station apparatus at stations "A" and "B" is well-known in the art and will not be described here. The operator's connective apparatus is likewise well-known in 35 the art and will therefore not be described, with the exception of the ringing key K , which is here shown in its operated or ringing position; the contacts r serving to connect the ringing generator D to the called 40 telephone line upon which is located the called sub-station "B." The ringing key K also consists of two pairs of contacts r_1 which serve at the same time to connect the ringing tone transmitting circuit C to the 45 connecting circuit conductors 1 and 2 leading back to the calling sub-station receiver R .

The vibrating bell being operated by means of its energizing circuit, including 50 the source of current E , its magnets m and its controlling contacts e , it is apparent that the gong G will be struck rapidly and thus be kept in a continual state of vibration, producing a ringing tone. The transmitter 55 T is arranged in close proximity to the gong G and its diaphragm (not shown) will be vibrated substantially in unison with the vibration of the gong G at all times. The source of electrical energy E_1 is here shown 60 as continuously flowing through the transmitter T over a circuit as follows: From the source of current E_1 , through the impedance coils l and the conducting wires 3 and 4, leading to the transmitter T . At the points 65 "5" and "6" a circuit is arranged in multiple

with the transmitter T as follows: From "6," through the condenser k , conducting wire 8, contacts S and c_1 and conductor 7, the primary winding p of the induction coil i and thus to the point "5." The vibration 70 of the transmitter diaphragm will in a well-known manner vary the transmitter resistance; the transmitter being connected in multiple with the circuit just described will therefore likewise vary the electrical potential existing at the points "5" and "6," and therefore cause a vibrating current to flow through this circuit corresponding to the vibrations of the transmitter diaphragm. It has been found that the bell tapper when 80 striking the gong, remains in contact with it long enough to interfere with its free or undamped vibration, and at this time produces a dull thudding sound, followed, when the tapper leaves the gong, by a new and 85 accelerated train of free vibrations. At the moment before, and while the gong G is struck by the tapper t , the circuit of the primary coil p will be broken at the contacts S and c_1 , consequently the tone current or 90 vibrating current will not flow at this time through the said primary winding, and the pounding sound of impact caused by the tapper striking, and thus momentarily damping the free vibration of the gong, will 95 not be transmitted back to the calling subscriber. However, the gong will continue to vibrate after being struck until the contacts S are again closed, the tapper at this time being at that part of its stroke distant 100 from the gong, and at this time the characteristic sound due to free vibration of the gong will be heard by the calling subscriber at "A" over the circuit which has been described, it being understood that the current 105 pulsations in the primary winding p are reproduced in the secondary winding s in the well-known manner, and such pulsations of current corresponding to the sound of the clear ringing bell will thereby be caused 110 to flow over the circuit leading to the calling subscriber's receiver R , through the condensers k_1 and over the wires w and w_1 , the contacts r_1 of the key K , the connecting circuit contacts 1 and 2, line wires 9 and 10, and 115 thence through the switch-hook contacts h at the sub-station "A" to the receiver R of the calling subscriber.

At Fig. 3 I show a portion of such a connective circuit as O except that in the connective circuit of Fig. 3 the ringing is accomplished in an intermittent manner and the intermittent ringing current is applied to the called subscriber's line by means of an electromagnetic key k_1 , after an initial 120 depression of a manually operated key K_1 . So far this operation does not differ from the method of automatic interrupted ringing as used in the art. In addition, I provide 125 the contact springs r , which in a manner 130

analogous to that just described for the manually operated key K of connective circuit O operate to connect the ringing tone current to the conductors 1 and 2 leading 5 back to the calling subscriber's telephone. I provide in addition, in the common tone supply leads w_2 and w_3 , interrupters z , which may rotate in synchronism with interrupter, g . In this way means are provided to transmit back to the calling subscriber an interrupted ringing tone which may correspond to the interrupted ringing 10 of the called subscriber's telephone bell. In Fig. 3 the electromagnetic key k_1 , and the manually operated key K_0 are both shown 15 in their unoperated position. Means are provided consisting of the trip relay 11 having contacts arranged so as to short-circuit the relay k_1 upon the response of the 20 called subscriber. By arranging the tone transmitting circuit through the contacts r , during the ringing period, I place the connection of the characteristic ringing tone circuit to the calling subscriber's telephone 25 under the control of the called subscriber's switch-hook since the response of the called subscriber will, in the well-known manner, operate the trip relay 11 which in turn short-circuits the electromagnetic ringing 30 key k_1 , which will deenergize, breaking its locking circuit through the contacts 12 and restoring the connection between the calling and called telephones by the closing of the talking circuit at contacts 13.

35 It will be understood that I do not limit myself to the precise method of producing the result above described but I am aware that other and numerous departures from the same can be made without departing 40 from the spirit of the invention, such as arranging a mechanical gong striking device and a mechanical contact making device, which could be arranged so that the contact of the tone producing circuit would be 45 closed after the gong receives the impulse causing its vibration. Such an impulse may be given by impact or any other way, such as electromagnetic attractions or repulsions upon a gong, which may be made 50 in such a case of steel.

What I claim as new and desire to secure by Letters Patent is:—

1. In a telephonic tone device, a vibratile member, means for actuating said member, a 55 telephone transmitter arranged in proximity thereto, a transmitting circuit for said transmitter, a telephone receiving circuit adapted to be connected thereto, and automatic periodic means for operatively disabling said telephone transmitting circuit at the time of actuation of said vibratile member by said actuating means.

2. In a telephone system, the combination 60 of a transmitter, a circuit therefor, a telephone receiving circuit, a vibratile sound-

ing member, striking means for said sounding member to cause said sounding member to sound a signal for a period of time, and periodic automatic disabling means to disable the said transmitter circuit for a first 70 portion of the said period of time.

3. In a telephonic tone device, a gong, a tapper for said gong, a telephone transmitter, a circuit therefor, and automatic periodic means for disabling said transmitter 75 circuit whenever said gong is struck by said tapper.

4. In a telephonic tone device, a gong, a tapper for said gong, a telephone transmitter, a circuit therefor, a telephone receiving 80 circuit, means for connecting said transmitter and receiving circuits, and automatic periodic means for disabling said transmitter circuit when said gong is struck by said tapper. 85

5. In a telephonic tone device, a vibratile member, means for actuating said member, a micro-phone, a transmitting circuit therefor, a telephone receiving circuit, electromagnetic means to connect said telephonic transmitting circuit to said receiving circuit, and automatic periodic disabling means to disable said transmitting circuit at the time of actuation of said vibratile 90 member. 95

6. The method of producing ringing tone currents consisting in causing a vibratile body to mechanically vibrate in a train of vibrations consisting of forced or damped vibrations and free vibrations, and translating only the free mechanical vibrations into corresponding electrical pulsations. 100

7. In a telephone system a calling and a called subscriber's line terminating in line jacks at a central office, a link circuit for connecting said lines in conversation, a source of ringing current associated with said link circuit and adapted to be impressed upon the line of said called subscriber, a tone signal member, means to actuate said member, means for converting the tone produced by said signaling member into current impulses of corresponding characteristics impressed upon said calling subscriber's line when said ringing current 105 is impressed upon said called subscriber's line and automatically operated disabling means for said converting means at the time of actuation of said tone signal member. 110

8. A telephone system, a calling and a called subscriber's line terminating in line jacks at a central office, a link circuit for connecting such lines in conversation, a source of ringing current associated with 115 said link circuit and adapted to be impressed upon the line of said called subscriber, a signaling device and actuating member, means to cause said member to actuate said signaling device, a telephonic 125

- element associated with said signaling device, periodic disabling means for said telephonic element, means for inductively connecting said telephonic element with the 5 talking strands of said link circuit and a controlling circuit changing member associated with last named connecting means whereby the calling subscriber is given a characteristic undamped tone whenever 10 said ringing current is applied to said line.
9. In a telephone system a calling and a called subscriber's line terminating in line jacks at a central office, a link circuit for connecting said lines in conversation, a 15 source of ringing current associated with said link circuit and adapted to be impressed upon the line for said called subscriber, a ringer, a tapper for said ringer, means to cause said tapper to actuate said 20 ringer, a telephonic element associated with said ringer, means for inductively connecting said telephonic element with the talking strand of said link circuit, an apparatus associated with said ringer whereby the calling 25 subscriber is given the sound of a bell ringing unmodified by the damping effect produced upon said bell by said tapper.
10. In a telephone system subscriber's line terminating at a central office, a link 30 circuit having one end connected with one of said lines, a source of ringing current,

means adapted to be actuated to impress current from said source upon the connected line, a source of ringing bell tone signaling current, means to cause the production from 35 the said source of undamped ringing bell tone signaling current and to prevent the production from the said source of damped ringing bell tone signaling current, and a switch operated upon actuation of said 40 means to connect said source of tone signaling current to the other end of said link circuit.

11. The method of producing ringing tone currents consisting of agitating a vibratile 45 body by an initial impulse causing the same to vibrate first in a forced manner and subsequently in a free manner, and translating only the free mechanical vibrations into corresponding electrical pulsations. 50

12. The method of producing a signaling tone current consisting of intermittently agitating a vibratile body causing successive mechanical trains of forced and free vibrations, and then translating only the 55 portion of each train which consists of free mechanical vibrations, into corresponding electrical pulsations.

In witness whereof, I hereunto subscribe my name this 28th day of November, A. D. 1916.

FRANK M. SLOUGH.
